FOUR-IN-HAND NECKTIE

Samuel L. Samter, Maurice L. Samter, and Joseph A. McCarthy, San Francisco, Calif., assignors, by mesne assignments, to Maurice L. Samter and Samuel L. Samter

Application June 4, 1935, Serial No. 24,862

6 Claims. (Cl. 2—155)

This invention relates to neckties and more particularly to a type of necktie generally known as a four-in-hand necktie and which may be tied and untied each time it is worn, or which may be ready-tied, and the four-in-hand knot remaining therein without untying same when the wearer puts on or takes off the tie. The invention includes several features of improvements upon four-in-hand ties, all of which will be more apparent as this specification proceeds. Four-in-hand neckties and the manner of forming a knot therein by wrapping one portion around another portion and looping an end portion through the wraps, are well known in the clothing art and no further general description of a four-in-hand tie is believed necessary.

Among the objects of the invention are to provide a four-in-hand tie having means in the neckband thereof by which the neckband may be connected and disconnected for putting on or taking off the tie, without untying the knot of the tie.

Another object is to provide a necktie having a severable neckband provided with a releasable connecting means which is not visible to view from the face-ply of the tie, and to provide a padding or cushion over such fastener to prevent a bulge being formed in the portion of the wearer's collar which overlies the fastener when the tie is being worn.

Another object of the invention is to provide a means to prevent the knot from slipping or sliding relative to that portion or leg of the tie which slides back and forth through the knot when the knot is tied.

A further object is to provide in a necktie of this character a means to prevent the small end of the tie from inadvertently being pulled through the knot, when the tie is loosened around the collar for removal by the wearer.

With the foregoing and other objects in view, all of which will be more apparent as this description proceeds, the invention is exemplified in the novel necktie construction hereinafter described, illustrated in the accompanying drawing, and pointed out in the claims hereto appended, it being understood that various changes in the form, proportion, size and details of construction of the apparatus may be resorted to within the scope of the appended claims without departing from the spirit or sacrificing any of the advantages of the invention.

To more clearly comprehend the invention, reference is directed to the accompanying drawing wherein:—

Fig. 1 is a front view of the invention showing

in skeleton the adaptation to what is known as a turn-down collar.

Fig. 2 is a front view of the tie prior to tying of the knot therein, partly broken away to show structure.

Fig. 3 is a fragmentary view of the reverse side of the tie showing a loop member through which one end portion of the tie is passed.

Fig. 4 is a lateral transverse cross-section on line IV—IV of Fig. 2.

Fig. 5 is a lateral transverse cross-section on line V—V of Fig. 2.

Fig. 6 is a fragmentary front view showing a modification of loop through which one end of the tie is passed.

Fig. 7 is a front view of the tie shown as adapted to an up-right collar.

Referring to the drawing, in which like characters of reference designate corresponding parts in the several views, 10 indicates generally a necktie of this invention which consists of a large end portion 11 and a small end portion 12, both formed of overlying layers of material 15, 17, with suitable liner 25 therebetween. The continuation of the small end portion 12 forms a neckband portion 13 which at its end opposite the end 12 is provided with one portion of a suitable releasable fastener member 14, which is herein illustrated by way of an example, as the socket portion of a snap fastener, which is set in the inner layer 15 of the neckband and reinforced at its mounting by a fabric washer 16 which may be a heavy woven fabric such as buckram or other similar material. The outer face ply 17 of the neckband covers over the top of the fastener member 14 as best shown in Fig. 4, so that the fastener is not visible from the outer face-ply of the tie, and for the further purpose of providing a padding or cushion overlying such fastener member to prevent the fastener from forming a bulge or perceptible lump in the visible surface area of the collar which overlies the fastener when the tie is being worn by a wearer. The large end 11 of the tie is provided adjacent its narrow end with a cooperating portion of a suitable releasable fastener member 18, such as a snap button which cooperates with the first mentioned fastener member 14 of the neckband portion of the tie for the purpose of connecting or disconnecting the two portions of the tie. The respective fasteners 14 and 18 may be mounted through the liner 25 for additional reinforcement purposes, as shown in Fig. 4. The fasteners and the joint for severance of the tie into two portions may be positioned at any portion of the neckband. For instance, in Fig. 1 the severance

Joint and the fasteners are positioned close to the portion of the tie where the knot will occur, whereas in Fig. 7 the severance joint and fasteners are shown at the rear of the collar and opposite the position at which the knot is tied. It is preferred, however, to generally place this severance joint of the necktie and the fasteners in close proximity to the position where the knot is to be tied.

10 Means are provided for determining and fixing the position of the knot with relation to the length of the tie, and to the fastener, and to prevent the knot being drawn or pulled so tight that the leg or small end will bind within the knot, said means as shown in Figs. 2 and 3, comprising a loop 20, preferably of flexible material which may be connected in any suitable manner to the tie body, as by having one end fastened under the fastener button 18, as at 21, and the other end 20 stitched to the tie as at 22, thus providing a loop through which the small end of the tie may be passed so that the position of the knot which is formed in the tie is definitely located and fixed at that position relative to the large end of the tie 25 and also relative to the severance joint and fastener; also, since the stress or pull on the tie will be against this loop rather than against the wrappings or windings of the knot, this loop prevents the knot from tightening to the extent that 30 it binds upon the leg of the small end which must be slidably therethrough.

The leg of the small end portion of the tie around which the large end portion is wound and looped to form the knot 23 is provided with a 35 reinforcing strip 24 throughout that portion or leg of said small end which slides back and forth through the tied knot 23 so as to prevent that leg portion of the small end of the tie which merges into the neckband from crimping laterally, or 40 what is termed "roping", and thus serves to preserve the flat normal condition of the tie and prevents the knot from slipping or falling away from the collar when the tie is being worn. This 45 reinforcing member is in addition to the usual liner 25 which extends throughout the length of each of the two portions of the tie in order to give the tie a body substance as shown in Fig. 4.

Since the roping of the tie will crimp it laterally, this reinforcing strip 24 is preferably made 50 of a woven fabric in which the longitudinal strands are relatively limp or lacking in substantial resistance to bending, whereas the strands which are laterally of the tie are more resistant to flexure. As an example of such a reinforcement the longitudinal strands may be made of such material as cotton and the lateral strands made of fiber or bristles so that the whole comprises what may be termed as hair-cloth with bristles running laterally only of the strip.

60 It is commercial practice to make ties inside out and then reverse them after the seam such as stitching 31 shown in Fig. 5, has been sewed. In this manner the reinforcing strip 24 may be sewed in the tie simultaneously with the making 65 of the seam. Both the liner 25 and the reinforcing member 24 may be further securely positioned within the tubular tie by overstitching 26 after the tie is turned inside out. However, this 70 overstitching is optional and is not a necessary part of the improved features of this invention.

75 While it is entirely practical to utilize this tie as a four-in-hand which is tied and untied by the wearer each time it is worn, it is preferred that when the knot is once tied it shall remain tied and the tie manipulated for the purpose of put-

ting it on and taking it off by means of the releasable fastener. However, in this mode of operation, it is desirable to loosen the tie slightly in the collar by sliding the knot for a short distance down the small end of the tie so as to make a slightly greater length to that portion of the neckband which goes around the collar and thus facilitate the connecting and releasing of the fastener, more particularly in the turn-down type of collar as shown in Fig. 1. Since the knot 10 is already tied, it is not desirable that the small end 12 shall pull out through the knot, to prevent which there has been provided a substantially rigid cross bar member 27 which is inserted laterally of the small end portion stitched into a 15 pocket 28 formed by a row of over-stitching above and below the cross bar 27, as at 29.

In Fig. 6 a modified means is shown for fixing the position of the knot with relation to the large end member of the tie. Instead of the loop 20 there is provided a slotted opening 30 through which the small end of the tie may be passed in like manner as it is passed through the loop of Figs. 2 and 3. In other respects, the modification of Fig. 6 operates similarly as the tie illustrated in Figs. 1 and 2.

Having thus described our invention, what we claim and desire to secure by Letters Patent of the United States is:—

1. A four-in-hand necktie comprising a large 30 end portion and a small end portion and a neckband portion therebetween, said tie including adjacent one end portion an elongated flexible reinforcing member longitudinally of the tie and having greater reinforcement capacity laterally 35 of the tie than longitudinally of the tie, said reinforcing member being positioned within a portion of the tie which is adapted for sliding through the knot in the tie, and adapted for resisting slipping of the tied four-in-hand knot when the 40 tie is being worn by a wearer.

2. In a four-in-hand necktie having a face ply and a back ply and comprising separate members including a large end portion and a small end portion and a neckband portion therebetween, 45 said neckband portion and one of said end portions each having adjacent a joining end thereof an internal reinforcement member and a member of a fastener means, said fastener members being connected to the internal reinforcement members and being cooperatively adapted for connecting and disconnecting said tie portions, the fastener member of one of said tie portions being mounted on the back ply of the tie and beneath the face ply of the tie whereby said 55 fastener member is hidden from view on the face ply of the tie portion to which it is attached.

3. In a four-in-hand necktie having a face ply and a back ply and comprising separate members including a large portion and a small portion and a neckband portion therebetween, said neckband portion and one of said end portions each having adjacent a joining end thereof an internal reinforcement member and a member of a fastener means, said fastener members being connected to the internal reinforcement members and being cooperatively adapted for connecting and disconnecting said tie portions, the fastener member of one of said tie portions being mounted on the back ply of the tie and beneath the face ply of the tie whereby said fastener member is hidden from view on the face ply of the tie portion to which it is attached, the small portion of said tie including intermediate its ends an elongated flexible longitudinal reinforcing member having 70 75 80 85 90 95 100

greater reinforcement capacity laterally of the tie than longitudinally of the tie, said reinforcement member being positioned within a portion of the tie which is adapted for sliding through the knot in the tie.

5. A four-in-hand necktie having a face ply and a back ply and a liner member therebetween, said tie comprising separate members including a large portion and a small portion and a neckband portion therebetween, said neck band portion and one of said end portions each having adjacent a joining end thereof a member of a fastener means, said fastener members being mounted through the liner of the tie and being 10 cooperatively adapted for connecting and disconnecting said tie portions, the fastener member of one of said tie portions being mounted on the back ply of the tie and beneath the face ply of the tie, and a stop means in the small portion 15 of the tie adjacent the free end thereof for resisting pulling of the free end portion out of the knot of the tie.

20. A four-in-hand necktie having a face ply and a back ply and comprising separate members including a large portion and a small portion and a neckband portion therebetween, said

neckband portion and one of said other portions each having adjacent one end thereof a member of a fastener means, said fastener members being cooperatively adapted for connecting and disconnecting said tie portions, the fastener member 5 of one of said tie portions being mounted on the back ply of the tie and beneath the face ply of the tie, said small portion of the tie including between its face ply and its back ply and adjacent its free end an elongated flexible reinforcing member longitudinally of the tie and having greater reinforcement capacity laterally of the tie than longitudinally of the tie.

25. A four-in-hand necktie having a face ply and a back ply and comprising a large end portion and a small end portion and a neckband portion therebetween, said small end portion of the tie including adjacent its free end an elongated flexible reinforcing member longitudinally interposed between the face ply and the back 20 ply, said flexible reinforcing member having greater reinforcement capacity laterally of the tie than longitudinally of the tie.
